TOASTER

John J. Rioux, Woodcliff Lake, N.J., assignor to Jet-Heet,
Inc., Englewood, N.J., a corporation of New York

Filed June 3, 1959, Ser. No. 56,196

Term of patent 14 years

(Cl. D81—10)

Fig. 3.

Fig. 4.

Fig. 5.

Fig. 1 is a front perspective view of a toaster showing the new design, illustrating the toaster in the open position;

Fig. 2 is a top plan view thereof as shown in Fig. 1;

Fig. 3 is a rear elevation of the toaster as shown in Fig. 1;

Fig. 4 is a front perspective view of the toaster as shown in Fig. 1 but illustrating the toaster in a closed position; and

Fig. 5 is a side elevational view thereof in open position.

I claim:

The ornamental design for a toaster, as shown.
